Human Samples Query				
And/Or	Field	Operator	Value	
None	Sample Origin	Equals	Number	
And	Sample Name	Contains	Sample	
And	Sample Creation Date	Equals	25-jan-2013	
	Sample ID	Sample Status	Sample Path	User
	Sample011	Checked In	SampleProcessor1 - Computer1	Mikhail Srivastav
	Sample010	Disposed	SampleProcessor1 - Computer1	Mikhail Srivastav
	Sample008	Checked Out	SampleProcessor1 - Computer1	Mikhail Srivastav
	Sample007	Checked In	SampleProcessor1 - Computer1	Mikhail Srivastav

The screenshot shows a software application window titled "Sample Tracker". On the left, a sidebar has a "Query" button and a "Human Samples Query" search bar. The main area has a table titled "Human Samples Query" with the following data:

And/or	Field	Operator	Value
None	Sample Origin	Equals	Human
And	Sample Name	Contains	Sample
And	Sample Creation Date	Equals	25-Jan-2013

Below this is a table titled "Sample List" with the following data:

Sample Id	Sample State	Storage Path	User
Sample011	Checked In	Escalator1 - Compactor...	Mithil Srivastav
Sample010	Disposed	Escalator1 - Compactor...	Mithil Srivastav
Sample008	Checked Out	Escalator1 - Compactor...	Mithil Srivastav
Sample007	Checked In	Escalator1 - Compactor...	Mithil Srivastav

At the bottom, there are buttons for "Back", "Check In", "Check Out", "Delete", "Dispose", and "New".
